(57) **CLAIM**

The ornamental design for an ultraviolet sterilizer for laundry purpose, as shown and described.

DESCRIPTION

1. Ultraviolet sterilizer for laundry purpose

1.1 : Perspective

1.2 : Front

1.3 : Back

1.4 : Left

1.5 : Right

1.6 : Top

1.7 : Bottom

The subject design relates to an ultraviolet sterilizer used to sterilize various types of bedding by transmitting ultraviolet rays from a bottom surface. The broken lines in Fig. 1.7 depict unclaimed portions of the ultraviolet sterilizer for laundry purpose, and form no part of the claimed design.

1 Claim, 7 Drawing Sheets
